UNITED STATES PATENT OFFICE.

DAVID J. BISSELL, JR., OF SPOKANE, WASHINGTON, ASSIGNOR TO OTIS AUTOMATIC TRAIN CONTROL INCORPORATED, OF SPOKANE, WASHINGTON, A CORPORATION OF WASHINGTON.

RAILROAD SAFETY SYSTEM.

Application filed May 1, 1923. Serial No. 635,895.

To all whom it may concern:

Be it known that I, DAVID J. BISSELL, Jr., a citizen of the United States, and resident of Spokane, in the county of Spokane and 5 State of Washington, have invented certain new and useful Improvements in Railroad Safety Systems, of which the following is a specification.

My invention relates to railroad safety systems, and has particular reference to improvements in apparatus for automatically controlling the movement of trains, whereby 10 collisions and other accidents of a like nature, due to carelessness, negligence or 15 incapacitation of an engineer and to other causes, may be averted.

With the foregoing and other purposes in view, my invention consists in the novel features of construction, combination and 20 arrangement of parts as will be hereinafter more fully described, illustrated in the accompanying drawings and defined in the appended claims.

In the drawings wherein like characters 25 of reference denote corresponding parts in the different views:

Figure 1 is a diagram showing the essential parts of my improved apparatus and the manner of relatively connecting the same;

30 Figures 2 and 3, elevations, respectively, of opposite sides of one of the ramp valves;

Figure 4, a transverse section through one of the ramp valves showing the same in normal "running" position;

35 Figure 5, a longitudinal section through the valve illustrated in Figure 4;

Figure 6, a detail section through a portion of the casing and core of one of the ramp valves;

40 Figure 7, a view similar to Figure 4 showing the operative position of one of the ramp valves;

Figure 8, a longitudinal section through the direction valve;

45 Figure 9, an end elevation of the direction valve;

Figure 10, a transverse section through the direction valve;

50 Figure 11, a longitudinal section through one of the ramp devices; and

Figure 12, a transverse section on the line 12-12 of Figure 11.

Referring now to the drawings in detail, it will be observed that the train carried 55 mechanism of my improved apparatus con-

sists of a pair of ramp valves A and B, the former for forward and the latter for backward running; a direction valve C to assure that the proper ramp valve is in operative relation to the braking mechanism according to the direction in which the train is moving or is to be moved; a speed control valve D operable to limit the speed of the train to predetermined rates under certain conditions, and a relief valve 60 E manually operable to permit the train to proceed cautiously within a predetermined low rate of speed as determined by the speed control valve, following operation of either 65 ramp valve.

The track mechanism consists of a number of duplicate ramp devices F arranged along the tracks in proper relation to the usual blocks and block signals, being operatively associated with the latter, so as to actuate 70 one or the other of the aforesaid ramp valves A or B, according to the direction of travel of the train, to cause a train attempting to enter an occupied block either to 75 stop or reduce its rate of speed to one of 80 caution or safety.

The ramp valves A and B which are as aforesaid, duplicates, each consists of a casing or housing 10 provided with a tapered, longitudinal bore 11 within which is rotatably mounted a plug valve 12, held in assembly with the casing in any preferred manner as by means of a removable cap or plate 13. Formed in said plug valve is an axial, tapered bore 14 that opens at its 85 smaller end through one end of the plug and at its other end is closed by a removable cap or plug 15. Within this bore is arranged a hollow, tapered sleeve 16 that is normally held by a coil spring 17 within the larger end of the bore, but that is capable of being moved against the force of said spring a predetermined distance in the direction of the smaller end of the bore, so as to come into snug, sealing contact with 90 the tapered wall of the latter. A key or spline 18 prevents rotation of this sleeve within said bore, and, as shown, the larger end of the sleeve is open, while its smaller end is provided with an aperture 16'.

Formed transversely through the sleeve 16 is a pair of ports 19 and 20, the former of which is elongated in the direction of the axis of the sleeve. These ports are spaced circumferentially of the sleeve and when the

said ports are alined, respectively, with the inner ends of another pair of ports 21, 22 that extend transversely through the plug valve 12 and at their outer ends are disposed relatively at an angle of substantially 45°. The ports 21, 22 are disposed in the same plane transversely of the plug 12 with each of three additional ports 23, 24 and 25, formed in the casing 10 and disposed relatively at the same angle as ports 21, 22. Accordingly, when the plug 12 is rotated to aline port 21 with port 24, port 22 will be alined with port 25, as shown in Figures 1 and 4 of the drawings, and when said plug is rotated to aline port 22 with port 24, port 21 will be alined with port 23 as shown in Figure 7 of the drawings.

Formed in the outer surface of the plug 12, at the same angle with respect to port 21 as port 22 and to the opposite side of port 21 as port 22, is another port 26 that is of limited depth and that is elongated in the direction of the axis of the plug. This port 26, when the parts 21, 22 are disposed, respectively, in alinement with ports 24, 25, is alined at one end with port 23 and at its other end with a small bleed opening 27 in the casing 10 leading to the atmosphere, but is moved out of alinement with port 23 and said bleed opening 27, so as to blank the latter when the plug is rotated to aline ports 21, 22 with ports 23, 24.

The means by which the plug 12 is adapted to be rotated consists of a depending ramp engageable shoe including a pair of arms 28, 29 connected together by a cross piece or pieces 30. One of these arms, 28, is non-rotatably connected with a projecting end of the plug 12, while the other arm, 29, is rotatably journaled on a stud 31 projecting from the casing 10, said stud carrying a double arm spring 32 that acts to hold said shoe normally in a vertical position with the ports 21, 22 alined respectively with ports 24, 25 and port 26 alined with ports 23, 27. Whenever the shoe is moved angularly to rotate the plug 12, the tendency of spring 32 is to restore both the plug and the shoe to normal position as is apparent.

Extending through the outer ends of arms 28, 29 is a hollow journal pin 33 for a roller 33', which roller is adapted to contact with a ramp to swing the shoe, and as a consequence, rotate the plug 12. The journal 33 is in the nature of a short length of pipe, one end of which is connected by another short, vertical length 34 with the open end of the bore 14 of the plug, while the other end is connected with a second short length 35 that extends upward through an offset in the arm 29 and is capped or otherwise closed as indicated at 35'.

spring 32 following actuation of the shoe by a ramp device. These latch devices are duplicates of one another and each consists of a pin 36 carrying a disk 37 that is slideable within a bore 39 in the casing 10, said pin, at its inner end, extending through a reduced portion of said bore into contact with the outer surface of the plug 12, and at its outer end being surrounded by an expansion coil spring 40 that reacts from a cap threaded on the casing in enclosing relation to the bore and pin, against the disk 37 to urge the pin inward into contact with the plug. In the plug is formed a recess 41 into which the inner end of the pin 36 is projected by the spring 40 to latch the plug against rotation when the shoe has been swung to aline the ports 21, 22 with ports 23, 24. Communicating with the inner end of bore 39 is a pipe 42 by which air under pressure may be introduced against the under face of disk 37 to force the same outward against the spring 40 and thus withdraw the pin from the recess 41 to unlatch the plug 12, whereby the latter may return automatically to its normal position under the influence of spring 32.

The two ramp valves A and B are secured, respectively, in any suitable manner, in reversed relation, on opposite sides of a locomotive, for cooperation with ramp devices located along opposite sides of the tracks, and they are connected together and with other parts of the apparatus in a manner which will be set forth in detail hereinafter.

Associated with each ramp valve is a slide valve for controlling the air supply to the bore 39 for releasing the latch pins 36, the slide valve in association with the forward running ramp valve, herein disclosed as being located on the right hand side of the locomotive, being located at some suitable point spaced well forward of said forward running ramp valve, preferably on the pilot of the locomotive, while the other slide valve in association with the backward running ramp valve, herein disclosed as being located on the left hand side of the locomotive, is located well to the rear of such backward running ramp valve, preferably on the tender of the locomotive. Each slide valve consists of a casing or housing 43 within which is vertically movable a block 44, one side of which is provided with a vertically elongated recess 45. This block has secured thereto the upper end of a rod 46 that depends through a brace or fixed support 47 and at its lower end is equipped with a ramp engageable roller 48. On said rod is a collar 49, and bearing downwardly on this collar is a coil spring 50 that urges said rod downward and as a consequence holds the

block 44 normally at its limit of downward movement within the casing 43, in which position of the block recess 45 communicates at one end with a part 51 in the casing to 5 which pipe 42 is connected, and at its other end communicates with a port 52 in the casing opening to the atmosphere. Thus, the bore 39 of the ramp valve is normally vented and subject only to atmospheric pressure, so 10 that the inward projecting influence of spring 40 against the pin 36 is unresisted.

Leading into the casing 43 is a pipe 53 by means of which the casing is constantly supplied with air under pressure. Consequently, whenever the block 44 is raised 15 sufficiently to uncover port 51, port 52 is simultaneously blanked and air is admitted from the casing into pipe 42 to retract the pin 36 from recess 41 and thus release the 20 latch as aforementioned. The rod 46 has only a limited amount of upward movement as determined by a suitable stop thereon engageable with the fixed support 47, and when it is at the limit of its upward 25 movement, roller 48 is disposed below the roller 33' of the ramp valve when the latter is in normal position, this for a purpose that will later appear.

The automatic direction valve C consists 30 of a casing or housing 54 provided with a tapered, longitudinal bore 55 within which is rotatably mounted a plug valve 56, said plug valve having formed therein an axial bore 57 of limited depth that communicates 35 at one end with a pair of hollow arms 58, 59 extending upwardly from the plug in diverging relative relation, and at its other end communicates with a pair of ports 60, 61 extending transversely of the plug. These 40 ports are disposed relatively at an angle of substantially 90° and in the same plane transversely of the plug with three ports 62, 63 and 64 formed in the casing 54, which latter ports, like the ports 60, 61, are disposed relatively at angles of substantially 45 90°. Accordingly, in one predetermined rotated position of the plug 56, ports 60, 61 will align, respectively, with ports 63, 64 and port 62 will be blanked, while in 50 another predetermined rotated position of the plug, ports 60, 61 will align, respectively, with ports 62, 63 and port 64 will be blanked.

The aforesaid direction 55 valve C is secured at any convenient location on the locomotive adjacent to a reciprocating part of the locomotive valve gear, preferably adjacent to the reach rod 65 connecting the usual reversing lever with the link 60 motion, a roller or other protuberance 66 being provided on said reach rod for cooperation with the hollow arms 59, 60, so that when the reversing lever is moved forward 65 to set the link motion and cylinder valves of the locomotive for forward running, said

roller will contact with arm 59 and as a consequence rotate the plug valve to align ports 60, 61 with ports 63, 64 and blank port 62, while vice-versa, when the reversing lever is moved to the rear to reverse the direction 70 of movement of the locomotive, said roller will contact with arm 58 and move the same to the rear and as a consequence rotate the plug 56 to align ports 60, 61 with ports 62, 63 and blank port 64. Only a limited 75 amount of movement of the reversing lever is required to impart the necessary rotation to the plug to align and disalign the ports mentioned, the arms 58, 59 being of such length that continued movement of the 80 reversing lever either forward or to the rear will result merely in the roller 66 moving beyond one or the other of the arms 58 or 59 as the case may be, in which connection it also will be observed that when 85 arm 59 is rotated forward by the roller 66, arm 58 is simultaneously rotated into position to be engaged by the roller when the latter subsequently is moved to the rear, and when arm 58 is rotated to the rear, 90 arm 59 is simultaneously rotated into position to be engaged by the roller when the latter subsequently is moved forward.

The automatic speed control valve D may be located at any convenient point on the 95 locomotive and, as shown, the same consists of a vertically arranged elongated casing or housing 67 within the upper end of which is slidably fitted a piston valve 68 having a rod 69 secured thereto and extending 100 above the casing where it is connected with governor mechanism 70 of any well known or preferred type, which governor mechanism is operated by a belt or gearing from one of the axles of the locomotive, or in 105 any other desired or preferred manner. Normally, that is, when the locomotive is at rest, the piston valve 68 is disposed at its uppermost limit of movement within the casing 67 and is moved downward by the 110 governor mechanism a greater or less distance according to the speed of the train as is manifest.

Provided in the casing 67 is an atmospherically opening port 71 that is blanked 115 by the lower end of the piston valve 68 when the latter is in its normal or uppermost position within the casing, but that is unblanked by an annular, elongated channel 72 in the piston valve when the latter is 120 moved a predetermined distance downward. The channel 72 is of such length as to at all times maintain communication with a port 73 in the casing directly above port 72, for all positions of the piston 125 valve within the limit of its downward movement.

Also slidably fitted within the casing 67, below the piston valve 68, is a second piston valve 74, that has a reduced lower end 130

- portion 47 operable within a similarly reduced portion 76 of the casing. The lower ends of both the piston 74 and its reduced portion 75 are formed as valves for cooperation with seats formed within the casing, so that when said piston is moved downward and said valves become seated, communication is cut off between a pair of ports 77, 78 located in opposite sides of the casing.
- 10 Extending downward from the reduced portion 75 of the piston 74 is a rod 79 that carries a valve 80, which valve normally is held closed against a seat surrounding an opening 81 in the lower end of the casing by a coil spring 82 that reacts against said valve from a cap 83 threaded on the lower end of the casing in enclosing relation to said valve. The rod 79 is of such length that when valve 80 is closed, the valves on piston 74, 75 are unseated, so that communication normally is established between ports 77, 78. When the piston 74, 75 is moved downward, however, and the valves thereof become seated to cut off communication between ports 77, 78, valve 80 simultaneously is unseated and port 77 is placed in communication with the atmosphere through opening 81 in the lower end of the casing and openings 84 in the cap 83.
- 15 20 25 30 Normally the pistons 68, 74 are relatively spaced and the latter is adapted to be moved downward by the former after the former has been moved downward a predetermined distance by the governor mechanism 70, the lower end of piston 68 being provided with a stud 85 that is adapted to contact with the upper end of piston 74 to accomplish this purpose. Stud 85 preferably is threaded in the piston 68, so that it may be adjusted 40 whereby a greater or lesser amount of downward movement of said piston 68 is necessary to move piston 74 downward for a purpose that will later appear.
- 35 40 45 50 55 60 65 The manual relief valve E which is preferably located in the cab of the locomotive consists of a casing 86 that is provided with a pair of valve chambers 87, 88 that have arranged therein, respectively, valves 89, 90 which valves are carried by a common stem 91, whereby they are movable in unison. Surrounding said stem and reacting from the casing 86 against valve 89 is a coil spring 92 that holds said valve 89 normally off its seat 93 and valve 90 normally closed with respect to a port 94 in the casing that opens into valve chamber 88. A knob 95 is provided on the stem 91, whereby said stem may be lifted manually to seat the valve 89 and simultaneously uncover port 94 to provide communication through valve chamber 88 between said port 94 and another port 96. Normally, however, spring 92 urges valve 89 off its seat 93 and valve 90 closed with respect to port 94 thereby normally to provide
- 70 75 80 85 90 95 100 105 110 115 120 125 communication through the valve chamber 87 between a port 97 and an atmospherically opening port 98 and at the same time deny communication between ports 94, 96. In other words, port 97 normally is vented through port 98 to the atmosphere and communication between ports 94, 96 is denied, but when valve 89 is closed to blank port 97, ports 94, 96 simultaneously are placed in relative communication.
- Each of the ramp devices F consists of an elongated substantially rectangular casing 100 to which casing is pivoted one of a pair of relatively hinged or pivoted ramp rails 101, 102, which ramp rails are adapted to be elevated to "danger" or ramp valve actuating position, and lowered to ineffective or "clear" position in a manner which will presently appear.
- Within the casing 100 is a lever 103 that is intermediately pivoted as at 104 and weighted at one end as at 105, whereby a roller 106 on its other end is held normally in contact with one of the ramp rails and said rails as a result held normally elevated. By this arrangement it is manifest that upon downward movement of that end of the lever 103 carrying roller 106, the influence of weight 105 upon the ramp rails is removed and said rails will as a result assume a horizontal or "clear" position under the influence of gravity.
- Within the casing 100 is mounted a solenoid 107, the core 108 of which is connected with lever 103 as indicated at 109, while the field thereof is located in a normally energized circuit including essentially the conductors 110, 111. In one of said conductors, herein shown as conductor 111, is a switch 112 that is maintained open by the weight 105 or lever 103 when said lever is in its normal position shown in Figure 11 holding the ramp rails elevated. Only a very small amount of depression of the ramp rails with corresponding depression of the roller 106 and slight raising of the weight 105 is necessary, however, to release said switch and permit the same to automatically close. Also arranged in one of said conductors is another switch 113 that is controlled by a float device 114, so that in the event of an excess quantity of water collecting within the casing 100 the circuit to the solenoid will be automatically broken. Conductors 110, 111 lead to suitable switches operated by the usual block signals, so that when a signal is set at "stop" or "caution" position, the circuit to the solenoid is deenergized, but is energized when the signals are in "clear" position.
- The operation of the ramp devices is apparent and as follows: When a block is clear and the usual signals so indicate that fact, the circuit through conductors 110, 111, although energized, is maintained broken

valve with one of the ramp rails 101, 102, with resultant slight depression of the ramp 5 rails and lifting of the weight 105, said switch will close and the solenoid field will become energized thus retarding the core 108 and allowing the ramp rails to fall under the influence of gravity to horizontal or 10 inactive position whereby the shoe of the ramp valve will be unaffected. The circuit will then remain closed until deenergized by movement of a signal to "stop" or caution position following which the ramp will 15 assume its normal status. On the other hand, if the signal controlling a given ramp is set at danger position, the circuit through conductors 110, 111 will be broken and the resistance of weight 105 to downward movement of the ramp rails will result in said rails remaining elevated so that when the shoe of a ramp valve strikes the same consequent actuation of such ramp valve will 20 result.

25 To connect the valves A, B, C, D and E with an ordinary air brake system, engineer's valve G for controlling the air supply from pipe 115, is connected through a four-way cock 116 with a pipe 117 leading to and connected with port 63 of direction valve C. From port 64 in said direction valve a pipe 118 leads to and is connected with port 25 of ramp valve A, while from port 62 in said direction valve a pipe 119 leads to and is connected with port 25 of ramp valve B. Port 24 of ramp valve B is connected by a pipe 120 with port 24 of ramp valve A and said pipe 120 is connected by another pipe 121 through four-way cock 116 with a pipe 122 leading to and connected with the train line pipe H. A by-pass pipe 123 connects pipes 117, 122 and in said by-pass pipe is a check valve 124 opening in the direction of said pipe 117. In said pipe 122 is a cut 45 off, double heading cock 125. Connecting pipe 117 with port 96 of the manual relief valve E is a pipe 126, while connecting port 94 of said relief valve with pipe 122 is a pipe 127. Connecting port 97 of the manual relief valve with port 73 of the automatic speed control valve D is a pipe 128, and branching off from this pipe 128 is a pair of pipes 129, 130 that lead to and connect, respectively, 50 with ports 23, 23 of the respective ramp valves A and B. Connecting port 77 of the automatic speed control valve D with the train line pipe H is a pipe 131, while connecting port 78 of said valve with train line pipe H is a pipe 132. Between pipes 131, 132 the train line pipe has interposed there- 55 in a normally closed cut off cock 133.

In Figure 1 of the drawings the plug 56 of direction valve C is shown as having been rotated to align ports 60, 61 with ports 62, 63 the mechanism then would be adapted for the automatic control of rearward movements of the train. In the position of the direction valve as indicated for controlling forward movement of the train the train line pipe H is charged from the supply pipe 115 by way of the 60 engineer's valve G, four-way cock 116, pipe 117, direction valve C, pipe 118, through ramp valve A, pipes 120, 121 back through four-way cock 116 and thence through pipe 122. Pipe 119 also is charged by way of pipe 120 and ramp valve B, but, as is apparent, this pipe is blanked at the direction valve C by the plug 56 closing port 62.

For controlling backward movements of the train, the plug 56 is, as aforesaid, rotated to align ports 60, 61 with ports 62, 63 and under such conditions, the train line is charged from supply pipe 115 by way of the engineer's valve G, four-way cock 116, pipe 117, direction valve C, pipe 119, through ramp valve B, pipes 120, 121 back through four-way cock 116 and thence through pipe 122. Pipe 118 also is charged by way of pipe 120 and ramp valve A, but, as is apparent, this pipe is blanked at the direction valve C by the plug 56 closing port 64.

Now, assuming that the train is moving ahead and attempts to enter an occupied block guarded by a ramp device F, the rails of which are elevated to danger or train stopping position; first, the roller 48 of the latch control valve in association with ramp valve A will engage with an inclined ramp approach rail 134 and be moved by said approach rail to its uppermost limit 105 of movement, as determined by the aforementioned stop on the rod 46 contacting with the fixed support 47, which upward movement will result in uncovering of port 51 and permit air from pipe 53 through 110 pipe 42 beneath disk 39. As the shoe of the ramp valve A is in vertical or normal running position, however, and the latch pin 36 already is raised and out of latching engagement with recess 41, the effect of this 115 introduction of air pressure beneath the disk 37 is nil; second, upon further forward movement of the train, roller 48 which is at its limit of upward movement contacts with and depresses ramp rails 101, 102, but 120 as the solenoid circuit is deenergized, said rails recover their elevated position under the influence of weight 105 immediately the roller has passed over the ramp, third, upon continued forward movement of the train, the shoe of ramp valve A contacts with the elevated ramp rails and due to the resistance of weight 105 against depression of said rails and the relative freedom of movement of the shoe, the latter, and with it the 125 130

jected into recess 41 to hold the shoe and plug against return to normal position 5 under the influence of spring 32. Rotation of the plug 12 to align ports 21, 22 with ports 23, 24 obviously places pipe 120 in communication with pipe 130 and results in blanking of port 25 and cutting off of the 10 supply through pipe 118. Thus port 72 of speed control valve D and port 97 of manual relief valve E are placed in communication with the train line pipe H through pipes 128, 130, ramp valve A, pipes 120, 121, four- 15 way cock 116 and pipe 122, and as port 97 is in communication with the atmosphere through valve chamber 87 and port 98, it is manifest that an exhaust of train line pressure will occur with resultant setting of the 20 brakes and stopping of the train. If the speed of the train is above a predetermined low rate and the piston valve 68 as a consequence is in uncovering relation to port 71 air will also be exhausted from the train 25 line through the speed control valve and will continue to exhaust through said valve until the speed of the train has been reduced sufficiently to cause the governor mechanism 30 to raise piston 68 and cover port 71. In the event it is desired to proceed into an occupied block at or below a predetermined low rate of speed, as determined by uncovering of port 71 by the governor mechanism 70, the engineman, knowing the block 35 to be occupied and accordingly having reduced the speed of his train, operates the manual relief valve to close valve 89 and thereby close port 98, so that when the shoe of the ramp valve engages a stop ramp and 40 is deflected to stop position, the brake pipe pressure will flow from pipes 122, 121, 120 to pipes 130, 128 where it will be confined and prevented from escaping to the atmosphere through either the speed control or 45 the relief valve, thus preventing a brake application. However, should the speed of the train at any time exceed the predetermined low rate, the brake pipe pressure would escape to the atmosphere through 50 port 71 of the valve D and a brake application would result. At the same time, the pressure on the under face of valve 89 would be relieved and spring 92 would force this valve off its seat and open communication 55 between pipe 128 and the atmosphere through port 98, so that should the speed of the train be automatically reduced, it will again be necessary to operate the manual relief valve. 60 The speed control valve D not only serves to maintain the train at or below a predetermined low rate of speed, but also serves to prevent the train exceeding a predetermined high rate of speed, for when the 65 governor mechanism 70 moves the piston forces the latter downward until the valves thereof engage their seats and cut off communication between pipes 131, 132. The supply through pipe 132 is thus blanked and simultaneously valve 80 is opened, resulting in an exhaust of pressure from the train via pipe 131, opening 81 in the lower end of valve D, and openings in the cap 83, with consequent setting of the brakes. Immediately, however, the braking effect of the brakes has reduced the speed of the train to a predetermined rate, say to sixty miles per hour, the governor mechanism 75 raises piston 68, allowing piston 80 to move upward under the influence of spring 82, reestablishing communication between pipes 131, 132 and closing valve 80, thus permitting the supply to recharge the train line 80 and release the brakes. This operation occurs regardless of any operation of other parts of the mechanism. 90 From the foregoing it is apparent that an engineman cannot move his train above a predetermined high rate of speed, nor can he, if he is alert and desires to proceed into an occupied block or zone at a predetermined low or cautious rate of speed, exceed such predetermined low rate so long as the block is occupied and the ramps guarding the same remain deenergized and set in stop position. Furthermore, if the engineman for any reason is absent from his post, in alert, careless or incapacitated and as a consequence fails to operate the manual relief valve E following actuation of either ramp valve A or B, his train will be brought 95 automatically to an immediate stop. On the other hand, if the engineman is alert and is proceeding through an occupied block at a permissible low or cautious rate of speed and said block becomes clear during this time, the next ramp that is passed over will 100 actuate roller 48 to operate valve 44 and release latch pin 36, allowing spring 32 to return the associated ramp valve to normal position, which normal position will be maintained due to the solenoid, which is now 105 energized, holding the lever 103 in position to permit the ramp rails to remain in depressed position, thus permitting the engineman to increase the speed of his train within its predetermined high rate as is apparent. 110 By the provision of sleeves 16 in the ramp valves A and B and by constructing said ramp valves as previously described, it is apparent that the hollow portions of the shoes thereof are at all times subject to train line pressure, so that in the event of a break or fracture occurring in a shoe, an exhaust of train line pressure will occur 115 with consequent setting of the brakes. The purpose of the sleeves 16 is to conserve 120

is in normal running position. The operation of sleeves 16 to accomplish this purpose is apparent: If a fracture or break occurs in a ramp shoe, the rush of air through the opening 16' in the smaller end of the related sleeve 16 will act to shift said sleeve 10 into the smaller end of and seal bore 14 and simultaneously disaline ports 20, 22, thus cutting off the supply. Due to the elongation of port 19, however, this port remains in registration with port 21 and air 15 will continue to exhaust from the train line. When the break has been repaired spring 17 returns sleeve 16 to normal position.

The hollow arms 58, 59 of direction valve C are, by reason of axial passage 57, subject to train line pressure in either forward or backward running position of said valve, and as a consequence, in the event of a break or fracture occurring in either or both arms, air will be exhausted from the train line and 25 as a result an application of the brakes and stopping of the train will be effected.

The purpose of bleed openings 27 in the ramp valves A and B is to relieve pipes 128, 129, 130 of air pressure following actuation 30 of either ramp valve and subsequent return of such valve to normal running position, whereby the pressure of air against valve 89 will be removed and this valve allowed to move off its seat to place the 35 aforesaid pipes in communication with the atmosphere through port 98, so that when a ramp valve is again operated, it will be necessary to manipulate the manual relief valve in order to prevent the train being 40 brought to a stop. Openings 27 are quite small, and while capable of relieving pipes 128, 129, 130 of pressure when the ramp valves are in normal running position, are incapable of permitting the exhaust of sufficient 45 air from said pipes to effect operation of the manual relief and speed control valves when a ramp valve is actuated.

From the foregoing description considered in connection with the accompanying drawings, it is believed that the construction, operation and advantages of my improvements will be fully understood. It is desired to point out, however, that various changes and desirable additions may be made 55 in and to the arrangements shown within the spirit and scope of my invention as defined in the appended claims.

I claim:

1. In a train control system; a train pipe, 60 ramp actuated means adapted in one position to establish communication between the train pipe and a pressure supply and in another position to close said communication and connect the train pipe with the atmosphere; and means operable while the

communication is established between the train pipe and a pressure supply.

2. In a train control system, a train pipe, a pair of ramp actuated mechanisms, means for rendering said mechanisms respectively operative and inoperative in harmony with the direction of train movement, each of 75 said mechanisms, when operative, being adapted in one position to establish communication between the train pipe and a pressure supply and in another position to close said communication and connect the train pipe with the atmosphere, and a single means operable, when either ramp actuated mechanism is operative and in said latter position, to simultaneously close the train pipe to the atmosphere and establish another communication between the train pipe and a pressure supply. 80 85

3. In a train control system, a train pipe, a ramp operated mechanism, a pressure supply pipe, a valve device connected to said pressure supply pipe, means leading from said valve device establishing connection between said ramp operated mechanism and the pressure supply pipe, and means leading from said valve device to the ramp operated mechanism and from said valve device to the train pipe establishing connection between the train pipe and ramp operated mechanism through said valve device. 90 95

4. In a train control system, a train pipe, a ramp operated mechanism, a pressure supply pipe, and a valve device connected to said pipe operable in one position to establish communication between the pressure supply pipe and ramp operated mechanism 100 and between the train pipe and ramp operated mechanism; and in another position to close communication between the train pipe and ramp operated mechanism and establish communication between the train pipe and pressure supply pipe through said valve device. 105 110

5. In a train control system, a train pipe, ramp actuated means adapted in one position to establish communication between the train pipe and a pressure supply; and in another position to close said communication and connect the train pipe with the atmosphere, and a pair of valve mechanisms for controlling the venting of the train pipe 115 120 through said ramp actuated mechanism, one of which is operated to vent the train pipe by a predetermined increase in train speed.

6. In a train control system, a train pipe, ramp actuated means adapted in one position to establish communication between the train pipe and a pressure supply; and in another position to close said communication and connect the train pipe with the atmosphere, and a pair of valve mecha- 125 130

train pipe through said ramp operated mechanism when said mechanism is in the latter position, one of said valve mechanisms being operable to simultaneously arrest said venting and establish another communication between the train pipe and a pressure supply and the other operated

crease in train speed while venting of the train pipe is arrested by the first named valve mechanism.

In testimony whereof I hereunto affix my signature.

DAVID J. BISSELL, JR.
